ADVERTISING COUPON DISPENSER

Homer B. Black, 4515 Garden Place 89109, and Ronald D. Ferderer, 1213 Las Vegas Blvd. S. 89104, both of Las Vegas, Nev.

Filed Feb. 1, 1973, Ser. No. 328,852

Term of patent 14 years

Int. Cl. D20—99

U.S. Cl. D52—2 R

FIGURE 1.

FIGURE 2.

FIGURE 3.

FIGURE 4.

FIG. 1 is a perspective view of an advertising coupon dispenser showing our new design;

FIG. 2 is a side elevational view thereof;

FIG. 3 is a front view thereof; and

FIG. 4 is an elevational view taken from the side opposite to that shown in FIG. 2.

The broken line representation of indicia in FIGS. 1 and 3 is for purposes of illustration only.

We claim:

The ornamental design for an advertising coupon dispenser, as shown and described.
